UNITED STATES PATENT OFFICE

JOHN J. KOHUT, OF ROCHESTER, NEW YORK

SHUTTER FOR AUTO HOODS AND LOCKING DEVICE THEREFOR

Application filed January 7, 1929. Serial No. 330,746.

The object of this invention is to provide an arrangement of a shutter on the inside of a hood covering the engine of an automobile, tractor or flying machine which can be opened and closed so as to provide ventilation of the space around the engine or to prevent ventilation of the space around the engine if desired.

Another object of the invention is to arrange the ventilating mechanism so that it may be more readily operated from the driver's seat or from the side of the car to permit ventilation or cut it off as may be desired.

Another object of the invention is to provide a device by which the shutter may be locked in any position desired.

These and other objects of the invention will be illustrated in the drawings, described in the specification and pointed out in the claims at the end thereof.

In the drawings:

Figure 1 is a perspective view of the inside of the hood showing the slats of the shutter and the mechanism for opening, closing and locking the slats.

Figure 2 is a longitudinal section through the handle and operating mechanism at the upper right hand corner of Figure 1, the handle being shown shoved into position for operating the shutter.

Figure 3 is a vertical section on the line 3x, 3x of Figure 2.

Figure 4 shows the shutter operating mechanism modified so as to work on slats which extend vertically instead of horizontally.

Figure 5 is a top plan view of a modified form of the operating mechanism for the shutter shown in Figure 4, the operating mechanism being shown placed on the outside of the hood.

In the drawings like reference numerals indicate like parts.

In the drawings reference numerals 1 and 2 indicate angle irons that are mounted on the inside of the hood. These angle irons are perforated at certain places indicated to receive the shafts 3, 4, 5, 6, 7, and 8 which have a bearing therein. These shafts carry the slats 9, 9 of the shutters which are formed of

sheet metal. One edge of each slat is rolled around the shaft on which the slat is mounted and the slat is fastened to the shaft by pins or set screws. On the end of each of the shafts 3, 4 etc. is fastened a pinion 10, 10 which turns with the shaft. Mounted adjacent to the angle iron 1 is a rack 11 which engages all of the pinions of the several shafts so as to compel all of the pinions and their shafts to move in unison. The topmost shaft is turned positively and this through the rack and pinions on the other shafts causes all of the shafts and slats to turn in unison with it. The rack 11 is perforated with the slots 12, 13 and 14 through which pass the studs 15 with nuts on the ends thereof by which the rack is held in place on the studs. The slots in the rack permit the rack to move endwise on the studs sufficiently to secure the opening and closing movement of the slats. The topmost shaft at the right hand end carries a pinion 16 that is integral therewith.

Mounted on the angle 2 is a curved rack 17 which extends down over the pinion 16. On the under side of the curved rack 17 are carried the teeth which are capable of engagement with the pinion 16. This rack is held in place by the bolt 18 at the top thereof, which holds it against endwise movement. At the lower end of the rack is a stud 19 which has a coil spring 20 around it, which bears on the lower end of the rack 17 and by which the rack is normally held in engagement with the pinion 16. This rack normally serves to lock the pinion against rotation and thus holds the slats of the shutter in whatever position in which they may have been placed.

The topmost shaft extends out to the handle 25. This shaft is divided as indicated at 26 and interlocking shoulders are formed on the ends between the two sections thereof. The shaft is divided near the line where the hood ends and the body of the car begins to permit lifting of the hood.

To give a firmer engagement between the interlocking shoulders on the ends of the two sections when they come together, the shaft itself is made larger in diameter in any suitable way, as by swaging or upsetting the end of the shaft or shrinking or brazing a sleeve

thereon. The outer section of the shaft may be built up in diameter in this same manner or a shaft of larger diameter may be used in the first place. Both sections of the shaft turn in the sleeves 28 and 29. The section 28 of the outer sleeve is fastened in a clamp 30 which holds it against movement either endwise or angular. The sleeve 29 is mounted to slide and turn in a socket 31. On the right hand end of the sleeve section 29 is fastened the handle 32. The handles 32 and 25 can both be moved to the right or left as may be desired; the sleeve 29 is surrounded by a spring 33 which is compressed between the socket 31 and the hub of the handle 32 so that the sleeve 29 is normally held in the right hand position shown in Figure 1. When the parts are in the position shown in Figure 2 the two sections of the shaft 27 are in engagement with each other at 26 and they can be turned as a unit by the handle 25 but they are normally locked against rotation by the rack 17 which is in engagement with the pinion 16.

Carried on the sleeve 28 is an arm 35 which engages under the lower end of the rack 17 and swings it away from the pinion. This arm is moved to lift the rack away from the pinion by the handle 32 and intermediate parts. When the handle 32 is moved to the right the handle 25 can be moved to turn the shafts 3 to 8 inclusive to open or close the slats. When the handle 32 is released the rack 17 will be pushed back into engagement with the pinion 16 by the spring 20 and the shafts will then be locked against rotation holding the slats of the shutter in the position in which they have been set.

In Figures 4 and 5 I have shown modifications of this device in which the slats 41 are mounted on a series of vertical shafts 42 to 47 inclusive etc. On the upper end of each of these shafts is provided a pinion 48 which pinion is engaged by a rack 49 by the endwise movement of which all of the slats are turned simultaneously. The shafts 42 to 47 inclusive are mounted to turn in angle irons 50 and 51 which are perforated to receive the shafts. The angle iron 50 carries the studs 52, 52 etc. which pass through slots 53 in the rack by which the rack is held in position and is permitted sliding engagement.

The rack 49 has an extension bracket 54 on the end thereof in which is swiveled a screw 55. This screw is threaded into a bracket 56 fastened on the hood. Mounted on the body of the car is a sleeve 57 which is free to slide in a socket 58 by which it is held in place. On the end of this sleeve is a handle 59. Around the sleeve and between the socket 58 and handle 59 is a spring 60 which normally holds the handle in position shown in Figure 4. The sleeve is slotted as indicated at 61 and engages with a cross pin 62 mounted in the screw 55. When the sleeve

is pushed the sleeve interlocks with the cross pin and the sleeve can then be turned for the purpose of turning the screw and moving it in either direction with the rack. This will cause the slats of the shutter to open or close as may be desired, and because of the threaded engagement between the screw 55 and bracket 56, the rack will remain locked in whatever position it may be left.

The screw 55 and the sleeve 57 are shown divided near the line where the hood ends and the body of the car begins to permit lifting of the hood.

In Figure 5 I have shown a handle 70 and a pinion 71 that engages with the teeth 72 formed on the top of the rack 49 by which this rack may be operated from the side of the hood instead of by means of a handle placed within the car. Otherwise the shutter operating mechanism is the same as is shown in Figure 4. The type of shutter and operating mechanism therefor shown in Figure 5 is probably more desirable in a tractor or flying machine while the shutter operating mechanism shown in the remaining figures is more desirable in an automobile.

It will be understood that a set of these shutters will be used on each side of the hood so as to permit ventilation across the hood through the shutters as well as to permit ventilation lengthwise through the hood through the radiator. In hot weather if the wind is blowing from the right, the shutter in the hood on the right will be set to catch the wind which will then blow across the engine and pass out on the opposite side of the hood or to the rear of the engine. If the wind is blowing from the left, the shutter on the left of the hood will be set to catch the wind which will then pass across the engine in the reverse direction and pass out on the opposite side of the hood, or to the rear of the engine. This adds greatly to the cooling of the engine.

I claim:

1. A shutter for an auto hood comprising a hood capable of being raised and lowered, a series of shafts mounted on said hood each having a slat mounted thereon and adapted to turn therewith, a pinion on the end of each shaft, a rack mounted on said hood engaging with all of said pinions by which they are all caused to move in unison, a shaft mounted on the hood connected with said rack and pinion combination for driving it, a shaft mounted on the frame of the car in line with the rack on the hood and adapted to move into and out of engagement with the shaft on the hood to turn the slats on the hood when the two shafts are in engagement, said shafts being placed in line with each other.

2. A shutter for an auto hood comprising a hood capable of being raised and lowered, a shutter thereon, a rock shaft mounted on the hood by which the shutter is operated, a

rock shaft mounted on the frame of the car in line with the shaft mounted on the hood when the hood is in its lowered position, said shaft on the frame of the car being adapted to move endwise into and out of engagement with the shaft on the hood to turn it and cause it to open and close the shutter on the hood.

3. A shutter for an auto hood comprising a hood capable of being raised and lowered, a shutter thereon, a shaft mounted on the hood by which the shutter is operated, a shaft mounted on the frame of the car in line with the shaft mounted on the hood when the hood is in its lowered position, said shaft on the frame of the car being adapted to move endwise into and out of engagement with the shaft on the hood to turn it and cause it to open and close the shutter on the hood, said 15 shafts being placed in line with each other, means for locking the shaft on the hood in a plurality of angular positions, said shaft thereby holding the shutter locked in a plurality of angular positions.

25 4. A shutter for an auto hood comprising a hood capable of being raised and lowered, a series of shafts mounted on said hood each having a slat mounted thereon and adapted to turn therewith, a pinion on the end of each 30 shaft, a rack mounted on said hood engaging with all of said pinions by which they are all caused to move in unison, a shaft mounted on the hood connected with said rack and pinion combination for driving it, a shaft mounted on the frame of the car and adapted to move into and out of engagement with the shaft on the hood to turn the slats on the hood when the two shafts are in engagement, said shafts being placed in line with each 35 other, a sleeve surrounding each of said last named shafts, one of said sleeves being on the hood and the other sleeve being on the frame of the car, a pinion on the shaft on the hood supporting said sleeve, a rack pivotally 40 mounted over said pinion and adapted to normally engage said pinion and lock it against turning, an arm on said sleeve on the hood adapted to engage the rack and swing it away from the pinion to release the pinion and 45 shaft for turning.

In testimony whereof I affix my signature.
JOHN J. KOHUT.
